UNITED STATES PATENT OFFICE.

SAMUEL G. STAYMATES, OF WALL, PENNSYLVANIA.

MAIL-CATCHER.

957,581.

Specification of Letters Patent.

Patented May 10, 1910.

Application filed October 2, 1909. Serial No. 520,691.

To all whom it may concern:

Be it known that I, SAMUEL G. STAYMATES, citizen of the United States, residing at Wall, in the county of Allegheny and State of Pennsylvania, have invented certain new and useful Improvements in Mail-Catchers, of which the following is a specification.

The object of this invention has been to devise a simple and novel construction of mail catcher adapted to effectively receive and support a bag of mail delivered from a moving train, and of a construction effective to eliminate likelihood of the mail being accidentally dropped and sucked beneath the moving train and destroyed.

The invention is of the type of mail catchers embodying diverging catching arms between which the bag of mail is caught and supported.

For a full understanding of the invention, reference is to be had to the following detail description and to the accompanying drawings, in which—

Figure 1 is a top plan view showing an apparatus built in accordance with the invention, the delivery hook of the mail car being illustrated in the position in which it delivers mail to the mail catcher, the arms of the catcher being shown in dotted lines in the positions assumed thereby after having been operated and in delivering a bag of mail; Fig. 2 is a side elevation of the mail catcher disposed in proper relation to a railway track, the delivery hook being arranged above the catcher as when delivering a bag of mail thereto; Fig. 3 is a transverse section on the line 3—3 of Fig. 1; Fig. 4 is a transverse section on the line 4—4 of Fig. 1, and Fig. 5 is a transverse section on the line 5—5 of Fig. 1.

Throughout the following detail description and on the several figures of the drawings similar parts are referred to by like reference characters.

Referring to the drawings and specifically describing the present invention the numeral 1 denotes a supporting post designed to be located at one side of a railway track in the customary manner and carrying a suitable supporting bracket 2 at the upper outer end portion of which is a head 3. Pivotally mounted on the head 3 are catcher arms 4 which when in their operative positions are held in divergent relation by means of a toggle joint 5 constituting a spreader in this

particular instance. The arms 4 are pivoted to a block 6 slideable on the head 3 and normally held in the position shown in Fig. 1 by means of a spring 7 interposed between the rear end of the head and the rear end of the block.

The purpose in providing the block 6 is to permit the arms 4 to yield rearwardly under the shock incidental to delivery of a bag of mail thereto. Projecting forwardly from the bracket 2 is a rigid horizontal arm 8 at the outer end of which is arranged a transverse guide 9. The guide 9 consists of a rectangular frame in which the arms 4 are adapted to slide toward and from one another. A pin 10 connecting the arm 8 and guide frame 9 forms an intermediate stop coöoperating with the arms 4 to prevent said arms from moving past a point centrally of the length of said guide. With each arm 4 is connected a weight 11, each weight being attached to a cord 12 which passes over a pulley on the arm 8 and is then connected with the arm 4 at the remote side of said arm 8. The tendency of the weights 11 is to force the arms 4 together or toward the dotted line position shown in Fig. 1. Mounted on each of the arms 4 is a buffer 13, said buffer comprising a casing in which is mounted a sliding plunger 14, the plunger having a head adapted to be engaged by the rear side of one member of the toggle 5, a spring 15 being provided and arranged in the casing of the buffer to hold the plunger 14 projecting outwardly therefrom in the position shown in Fig. 1. The object in providing the buffers 13 is to employ a means in rear of the toggle 5 to engage the members of said toggle when the said members are struck by the mail bag, and to relieve somewhat the concussion incidental to the delivery of the sack of mail from the hook 16 on the mail car to the catcher.

In the actual use of the invention the parts are in the normal positions shown in Fig. 1. As a train passes the sack or bag of mail is supported on the hook 16 which travels above the arms 4 and is adapted therefore to deliver the sack of mail to the catcher, the sack striking the horizontal portion of the toggle 5 and breaking the joint by forcing the members of the toggle rearwardly. The above action causes the toggle members to grip the sack of mail at opposite sides and forces the arms 4 inwardly, the action being assisted by the weights 11. When the sack

of mail strikes the members of the catcher the shock is relieved also by rearward movement of the block 6 to which the arms 4 are pivoted, such rearward movement compressing the spring 7.

5 The spring may be substituted for the weights 11 so as to tend to force the arms 4 together when the toggle joint 5 is broken.

Having thus described the invention, what 10 is claimed as new is:

1. A mail catcher comprising a supporting bracket, spaced arms pivotally mounted on said bracket, a spreading toggle joint connecting adjacent end portions of said 15 arms and normally holding them in spaced relation, and buffers carried by the arms and engageable with the members of the toggle joint when said joint is broken by impact of a sack of mail therewith.

2. In a mail catcher, the combination of a 20 supporting bracket having a head thereon, a block yieldingly mounted to slide on said head, catcher arms pivoted at their rear ends to the head, a toggle joint connecting the front end portions of the arms to hold the 25 same apart, buffers carried by the arms to engage the members of the toggle joint when said joint is broken, means normally tending to force the catcher arms together, and a guide in which the catcher arms slide intermediate of their ends.

In testimony whereof I affix my signature in presence of two witnesses.

SAMUEL G. STAYMATES.
